CLAIM

The ornamental design for a hinge component for an electrical equipment mounting, as shown and described.

DESCRIPTION

FIG. 1 is a perspective view of the hinge component for an electrical equipment mounting showing my new design;

FIG. 2 is a front elevational view thereof;

FIG. 3 is a left-side elevational view thereof;

FIG. 4 is a right-side elevational view thereof;

FIG. 5 is a rear elevational view thereof;

FIG. 6 is a top plan view thereof; and

FIG. 7 is a bottom plan view thereof.

A contact is shown in broken lines in FIG. 1 for illustrative purposes and form no part of the claimed design.

FIG. 1

FIG. 3

FIG. 2

FIG. 5

FIG. 4

FIG. 6

FIG. 7
